Fig. 5.

FIGURE 1 is a side elevational view of the nebulizer, illustrating my new design, with the discharge tube closure cap in a closed position.

FIGURE 2 is an elevation thereof, with the closure cap in an open position.

FIGURE 3 is an end elevation of the nebulizer, looking to the right in FIGURE 1.

FIGURE 4 is a similar view, but with the closure cap in the open position.

FIGURE 5 is a side elevational view of the nebulizer, with parts in position corresponding to FIGURE 1, but from a view point at right angles to that of FIGURE 1.

FIGURE 6 is an enlarged isometric view of the nebulizer, with the bulb member fragmentarily shown for convenience of illustration.

The dominant features of my design reside in the portions shown in full lines.

I claim:

The ornamental design for a nebulizer, substantially as shown and described.
